US0D1056243S

(12) **United States Design Patent** (10) **Patent No.:** **US D1,056,243 S**
(45) **Date of Patent:** **** Dec. 31, 2024**

(54) **TEST CARD FOR LIQUID SAMPLES**

(71) Applicant: **Hangzhou Biotest Biotech Co., LTD.**,
Hangzhou (CN)

(72) Inventors: **Shujiang Wu**, Hangzhou (CN);
Junsheng Wu, Hangzhou (CN); **Yang Wang**, Hangzhou (CN); **Liang Hong**, Hangzhou (CN)

(73) Assignee: **HANGZHOU BIOTEST BIOTECH CO., LTD.**, Zhejiang (CN)

(**) Term: **15 Years**

(21) Appl. No.: **29/870,978**

(22) Filed: **Feb. 9, 2023**

(30) **Foreign Application Priority Data**

Dec. 8, 2022 (CN) 202230822760.6

(57) **CLAIM**

The ornamental design for a test card for liquid samples as shown and described.

DESCRIPTION

FIG. 1 is a front top perspective view of the test card for liquid samples showing our new design;

FIG. 2 is a front bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the test card for liquid samples that form no part of the claimed design.

1 Claim, 8 Drawing Sheets
